UNITED STATES PATENT OFFICE.

GEORGE H. WILLIAMS, OF KANSAS CITY, MISSOURI.

GRADUATED REINFORCED ANGLE-BAR AND RAIL-SHOE COMBINED.

SPECIFICATION forming part of Letters Patent No. 735,025, dated July 28, 1903.

Application filed April 16, 1903. Serial No. 152,841. (No model.)

To all whom it may concern:

Be it known that I, GEORGE H. WILLIAMS, a citizen of the United States, residing at Kansas City, in the county of Jackson and State 5 of Missouri, have invented new and useful Improvements in a Graduated Reinforced Angle-Bar and Rail-Shoe Combined, of which the following is a specification.

My invention relates to an improvement on 10 my reinforced angle-bars covered by Letters Patent No. 714,422, dated November 25, 1902; and the object of the present invention is to provide a base-support for the ends of the rails as well as the support of the graduated 15 angle-bars under the head of the rails at their ends, giving a double support to the rails at their ends, so as to more effectually resist the blows of the passing car-wheels.

My improvement consists in providing each 20 graduated reinforced angle-bar with an integral bifurcated rail-shoe which is adapted to embrace and support the base-flanges of the rail, as described hereinafter. These rail-shoes should be supported by one of the regular 25 ties of the road-bed, and hence I would term the two improved angle-bars applied to the ends of two rails a "tie" joint as distinguished from a "suspended" joint, or one occurring between two ties.

Referring now to the accompanying drawings, Figure 1 is a plan view of a tie-joint composed of two of my improved bifurcated angle-bars, the ends of three ties being shown. Fig. 2 is a transverse section taken on line 35 *a a* of Fig. 1. Fig. 3 is a transverse section taken on line *b b* of Fig. 1. Fig. 4 is a transverse section taken on line *c c* of Fig. 1.

1 and 2 designate the graduated reinforced bifurcated angle-bars, which are secured to 40 the ends of two meeting rails 3 by ordinary binding-bolts 4. The reinforced portions of these angle-bars are formed in the same manner as those of my Patent No. 714,422, Fig. 1, or they may be modified with respect to 45 their reinforcements, as illustrated in Fig. 5 of said patent. 6 and 7 designate the under

portion of the bifurcations, the conformation of which is most clearly shown in Fig. 3. Each of said bifurcations has an outwardly-projecting flange 8, through which spike-holes 50 are punched, whereby said flanges may be spiked down to the tie 9. Said under portions 6 7 extend inwardly beneath the bases of the rails, thereby affording rigid support to the ends of the rails. The length of each bifurcated portion should be approximately equal to the width of a standard tie, which is eight 55 inches.

Because of the limit of metal bearing of the angle-bar under the heads of the rails, the bifurcated portions, resting upon a cross-tie, afford the rail-joints a more perfect and rigid support in resisting the blows of the car-wheels and weight of the passing trains.

It will be observed that the foot-flanges of 65 my improved angle-bars are cut away narrower than the foot-flanges of the rails. The purpose of this reduction in the width of the angle-bar flanges is to eliminate surplus metal.

Having now fully described my invention, what I claim as new, and desire to secure by Letters Patent of the United States, is—

In a bifurcated graduated reinforced angle-bar of the character described, the combination of two abutting ends of railway-rails, the angle-bar adapted to engage said abutting ends, the upper portion thereof recessed, the lower portion bifurcated longitudinally at their centers and adapted to correspondingly engage the base portion of the ends 75 of the rails, lateral extensions adapted to receive rail-spikes, binding-bolts passing through the body portion of the bars and the web of the rails, substantially as described. 80 85

In testimony whereof I affix my signature in the presence of two witnesses.

GEORGE H. WILLIAMS.

Witnesses:

GEO. H. ROBERTS,
E. G. CHEESMAN.
